United States Patent Office

Des. 218,890
Patented Oct. 6, 1970

218,890

CASKET CARRIER

Leonard Kreminski, 12224 Eckleson Place,
Cerritos, Calif. 90701

Filed June 23, 1969, Ser. No. 17,818

Term of patent 3½ years

Int. Cl. D31

U.S. Cl. D19—1

The single figure is an isometric view of a casket carrier, showing my new design, the opposite side and end being substantially mirror images, respectively, of the side and end shown.

I claim:

The ornamental design for a casket carrier, substantially as shown and described.
